UNITED STATES PATENT OFFICE.

WILLIAM S. ELLIOTT, OF SOPER, OKLAHOMA.

DESIGN FOR A GUITAR OR SIMILAR ARTICLE.

Application filed November 3, 1928. Serial No. 28,758. Term of patent 14 years.

To all whom it may concern:

Be it known that I, WILLIAM S. ELLIOTT, a citizen of the United States, residing at Soper, in the county of Choctaw and State of Oklahoma, have invented a new, original, and ornamental Design for a Guitar or Similar Article, of which the following is a specification, reference being had to the accompanying drawing, forming part thereof.

The figure is a view in a perspective of a guitar or similar article embodying my design.

I claim:

The ornamental design for a guitar or similar article, as shown.

WILLIAM S. ELLIOTT.
